RICHARD E. SPERRY, OF GREENWICH, CONNECTICUT, AND RICHARD E. TALMADGE, OF NUTLEY, NEW JERSEY, ASSIGNEES TO MACARTHUR CONCRETE PILE CORPORATION, OF NEW YORK, N. Y., A CORPORATION OF NEW YORK

PILE STRUCTURE

Application filed May 28, 1930. Serial No. 456,398.

This invention relates to pile structures.

More particularly stated, the invention relates to composite piles, such as piles comprising wood and concrete sections.

5 The invention has for its salient object to provide simple, practical and efficient means for anchoring the two sections of the pile together.

Another object of the invention is to provide means for anchoring a form or casing in which the concrete is joined to the wood section of the pile, so constructed and arranged that the casing will be securely anchored and held against lifting or relative movement with respect to the wood section when the form or casing is filled with concrete.

Further objects of the invention will appear from the following specification taken in connection with the drawings, which form a part of this application, and in which

Fig. 1 is an elevational view of a composite pile constructed in accordance with the invention;

25 Fig. 2 is a longitudinal sectional elevation taken at right angles to Fig. 1;

Fig. 3 is an elevational view of the upper end portion of the wood section of the pile;

Fig. 4 is a top plan view of the structure 30 shown in Fig. 3; and

Fig. 5 is a view similar to Fig. 3 but showing a slightly modified form of construction.

The invention briefly described consists of 35 a composite pile comprising a pair of sections, one preferably formed of wood and the other of concrete. The invention may be used, however, to join two concrete sections. One section, such as the wood section, has a reduced upwardly extending end and a rod 40 is secured to the end and extends transversely therethrough. The other, or concrete section, has an outer casing or form within which the concrete is poured. The lower end of the casing has slots for receiving the ends of the rod and anchoring the casing to the rod and wood pile section. A pan or cup-shaped flange is preferably placed on the lower or wood section of the pile and rests 45 on the shoulder formed between the main

body portion of the wood section and the reduced end. The casing or form rests at its lower end on the flange or pan.

Further details of the invention will appear from the following description.

In the particular embodiment of the invention illustrated in the drawings, there is shown in Fig. 3 the upper end portion of a wood pile comprising a main body portion 10 and a reduced upper end portion 11. It should be understood, however, that this pile section may be formed of concrete, if desired. A pan 12 having a central opening 13 is placed over the reduced upper end or tenon 11 and rests on the shoulder 14 formed at the juncture of the portions 10 and 11 of the wood section of the pile.

A rod 15 is secured to the portion 11 and extends therethrough, as shown in Fig. 3.

The concrete or upper section of the pile is enclosed within a shell or casing 20 which is provided at its lower end with diametrically disposed bayonet slots 21 and 22 which extend upwardly from the lower end of the shell and substantially at right angles to the axis of the shell. The portions of the shell having the slots formed therein are preferably reinforced by plates 23 and 24 which are slotted in a manner similar to the lower end of the shell. If desired, the slots 21A and 22A may be formed in the plates 23 and 24 only (as shown in Fig. 5) and not in the shell.

Reinforcing means may be placed around the tenon or reduced end 11 such, for instance, as the reinforcing rods 25 and wire 26. The rods and wire are preferably placed in position before the shell is secured. The shell is then placed around the tenon or reduced end 11 and locked thereto by the rod and bayonet joints. The rod and coacting portions of the shell securely hold the casing or shell down so that the shell will rest in the pan 12, as shown in Fig. 2. The concrete is then poured into the shell and surrounds the rod and tenon or extension 11.

From the foregoing description it will be seen that a simple, practical and efficient composite pile has been designed and that

the shell or casing will be securely anchored to the lower section of the pile.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What we claim is:

1. A composite sectional pile comprising a section having a reduced end, a rod extending transversely through said end, a concrete section comprising a metallic casing having a reinforcing means at its lower end provided with longitudinal slots adapted to receive the ends of said rod and angular slots communicating therewith, whereby the casing is locked to said rod, and concrete filling said casing and surrounding said rod and reduced end.

2. A composite sectional pile comprising a section having a reduced end, a rod extending transversely through said end, a concrete section comprising a metallic casing having a reinforcing means at its lower end, said reinforcing means being provided with longitudinal slots adapted to receive the ends of said rod and angular slots communicating therewith, whereby the casing is locked to said rod, said casing end extending about said reinforcing means and about the ends of said rod whereby to enclose the same, and concrete filling said casing and surrounding said rod, reduced end and reinforcing means.

3. A composite sectional pile comprising a section having a reduced end, a rod extending transversely through said end, a concrete section comprising a metallic casing having a reinforcing means at its lower end, said reinforcing means and lower casing end being provided with longitudinal slots adapted to receive the ends of said rod and angular slots communicating therewith, whereby the casing is locked to said rod, and concrete filling said casing and surrounding said rod and reduced end.

4. A composite pile comprising a wood section having a tenon at one end, a rod carried by and extending through said tenon, a pan surrounding the tenon, a metal shell surrounding the tenon and resting at its lower end in said pan, said rod also extending through the lower end of said shell whereby to lock the shell to the wood section and in the pan, and concrete filling said shell.

5. A composite pile comprising a wood section having a tenon at one end, a pair of projections extending laterally from said tenon, a pan surrounding the tenon, a metal shell surrounding the tenon and resting at its lower end in said pan, said projections also extending through the lower end of said

shell whereby to lock the shell to the wood section and in the pan, and concrete filling said shell.

6. A composite pile comprising a wood section having a tenon at one end, a rod carried by and extending through said tenon, a pan surrounding the tenon, a concrete section having its lower end resting in said pan and comprising a metallic casing having a reinforcing means at its lower end, said reinforcing means being provided with longitudinal slots adapted to receive the ends of said rod and angular slots communicating therewith whereby the casing is locked to said tenon and in the pan, said casing end extending about said reinforcing means and about the ends of said rod whereby to enclose the same, and concrete filling said casing and surrounding said rod, reduced end, and reinforcing means.

In witness whereof, we have hereunto set our hands this 21st day of May 1930.

RICHARD E. SPERRY.

RICHARD E. TALMADGE.
